SNUBBED BOLSTER TRUCK

Walter L. Schlegel, Jr., Chicago, Ill., assignor to
American Steel Foundries, Chicago, Ill., a corporation of New Jersey

Application August 17, 1945, Serial No. 611,008

1 Claim. (Cl. 105—197)

1 The invention relates to railway car trucks and more particularly to a truck incorporating a snubbing device by means of which frictional control is afforded of the oscillations of the bolster-supporting spring group.

An object of the invention is to design a snubbed truck incorporating a snubbing device which operates to develop a greater degree of friction in one direction of movement of the bolster than in the opposite direction of movement for preventing synchronous oscillations of the bolster-supporting spring group.

A specific object of the invention is to design such a truck as above described wherein friction shoes are housed in the bolster at opposite sides thereof in engagement with wedge means supported on resilient means, the resilient means being seated on the side frame and operatively urging the wedge means into engagement with the shoes and the shoes into frictional engagement with the adjacent side frame columns.

The invention contemplates an arrangement such as above described wherein each friction shoe is engaged along arcuate surfaces by the wedge means and a wall of the bolster in such manner as to allow relative angling movement of the bolster and side frame without disrupting the frictional engagement of the shoes with the side frames.

In the invention, I employ a novel shoe and wedge, the shoe comprising a main friction wall having a friction face on one side thereof, and a substantially horizontal wall and diagonal wall projecting from said friction wall, the diagonal wall presenting a V-shaped wedge surface crowned from top to bottom, and the horizontal wall presenting an arcuate surface, and the wedge comprising a member having spaced substantially horizontal walls, and lateral walls presenting reversely arranged diagonal V-shaped surfaces, one of said horizontal walls providing a spring seat.

The foregoing and other objects and advantages of the invention will become apparent from the following specification and the accompanying drawings, wherein:

Figure 1 is a fragmentary side elevation of a railway car truck embodying the invention, partly in section, said section being taken in a longitudinal vertical plane approximately bisecting the side frame as indicated by the line 1—1 of Figure 2;

Figure 2 is a fragmentary top plan view of the structure shown in Figure 1 with the side frame shown in section through the columns thereof;

Figure 3 is a fragmentary sectional view taken

2 in the transverse vertical plane indicated by the line 3—3 of Figure 1;

Figures 4 and 5 illustrate in detail the friction shoe utilized in the arrangement of Figures 1—3, Figure 4 being a side elevation of the shoe, and Figure 5 being a bottom plan view thereof;

Figures 6 and 7 illustrate in detail the wedge member utilized in the arrangement of Figures 1 and 3, Figure 6 being a side elevation thereof, and Figure 7 a top plan view thereof.

Describing my novel snubbed truck in detail, the side frame comprises tension and compression members 2 and 4 connected at each end of the frame by a column 6 defining the bolster opening 8 having a widened lower portion 10 for a purpose hereinafter more fully described.

The tension member is of conventional box section with the top chord 11 thereof affording a seat 12 (Figure 1) for the bolster-supporting spring group comprising the main coil springs diagrammatically indicated at 14, 14 and an auxiliary coil spring 15 disposed centrally of the group and serving a purpose hereinafter described. The tension member is formed with an upstanding flange 16 on the inboard and outboard sides thereof to afford convenient confining means for the lower ends of the springs 14, 14. The upper ends of the springs 14, 14 are afforded a seat as at 18 (Figure 1) for the bolster generally designated 20, said bolster being of box section and comprising the spaced side walls 22 and 24 and the top and bottom walls 26 and 28 and having a pocket or passage 30 extending transversely therethrough between the columns 6, 6 of the side frame 2, said pocket being defined by inboard and outboard webs 32 and 34 and the top and bottom walls 26 and 28, said top wall having a substantially plane surface 35 for engagement with associated friction shoes, as hereinafter described.

The bottom wall 28 of the bolster is formed centrally thereof with a thickened portion providing an annular opening 36 through which extends the coil spring 15 having its lower end seated as at 40 on the spring seat 12 of the side frame tension member 2 centrally of the bolster-supporting spring group and having its upper end confined within said opening 36 and bearing as at 42 against an associated wedge member supported thereon.

Received within the transverse passage 30 of the bolster is a wedge member or bearer, sometimes designated an equalizer, generally designated 44, said member 44 being shown in detail in Figures 6 and 7 and being a boxlike structure comprising top and bottom walls 46 and

48 merging at opposite ends thereof with spaced reversely arranged diagonal walls 50, 50 sloping downwardly and outwardly toward the columns 6, 6, each diagonal wall 50 presenting a V-shaped wedge surface 52 for engagement with an associated friction shoe. The wedge member 44 also comprises a centrally disposed depending lug 54 on its bottom wall 48 for reception within the upper end of the spring 15 seated against said wall as at 42, said lug 54 serving 10 as positioning means for the spring 15.

At each side of the bolster within the passage 30 is disposed a friction shoe, generally designated 56, and one of said shoes is shown in detail in Figures 4-6 inclusive. It will be apparent from a consideration of these figures that the shoe is a casting cored away as at 58 to lighten the same, and said shoe comprises a friction wall 60 presenting a friction surface 62 for engagement as at 64 with the adjacent column-mounted wear plate 66, said shoe also comprising a substantially horizontal wall 68 for engagement as at 70 with the surface 35 on the top wall 26 of the bolster, and a diagonal wall 72 connecting the walls 60 and 68 and presenting a V-shaped wedge surface 74 for engagement as at 76 with the wedge surface 52 of the adjacent wall 50 of the equalizer member 44. It will be seen from a consideration of Figures 1 and 4 that the wedge surface 74 of the shoe is crowned from top to bottom, and the wall 68 of the shoe is crowned from end to end to afford the rocking motion thereof against the surface 52 of the wedge member 44 and the surface 35 of the bolster wall 26, respectively, whereby upon vertical angling movement of the side frame relative to the bolster, the bolster will remain in its desired normal horizontal position without impairment of the frictional engagement of the shoes with the wear plates 66, 66 of the columns 6, 6.

It will be apparent that the compression of the spring 15 between the side frame tension member 2 and the wedge member 44 will cause the latter member to be constantly urged upward in the bolster passage 30 to thereby urge the associated shoes 56, 56 into wedge engagement therewith and into sliding engagement with the bolster top wall 26 in a direction outwardly of the bolster and into frictional engagement with the column wear plates 66, 66, whereby, upon vertical movement of the bolster within the bolster opening, a greater amount of friction will be developed on the downstroke of the bolster than on the upstroke thereof, inasmuch as the compression of the spring 15 is increased on the downstroke of the bolster, resulting in the shoes being urged into frictional engagement with the columns with greater force than on the upstroke of the bolster, the resultant frictional engagement of the shoes and side frame wear plates effectively dampening the oscillations of the bolster-supporting spring group while obtaining frictional absorption proportionate to the load carried by the bolster and maintaining this condition substantially without variation until ultimate wear has occurred between the engaged surfaces.

In the embodiment of the invention described above, the bolster is guided in its vertical move-

ment by the inboard and outboard guide lugs 76 and 78 at each side thereof, said guide lugs 78, 78 being of less depth than the distance A between the flanges 16 of the tension member 2 and the guide portions 80, 80 of the side frame columns 6, 6 defining the widened lower portion 10 of the bolster opening 8 to permit the convenient assembly and disassembly of the bolster and side frame, as will be apparent to those skilled in the art.

It is to be understood that I do not wish to be limited by the exact embodiment of the device shown which is merely by way of illustration and not limitation as various and other forms of the device will, of course, be apparent to those skilled in the art without departing from the spirit of the invention or the scope of the claim.

I claim:

20 A railway car truck including a side frame having spaced columns and a bolster opening therebetween, a bolster portion disposed between said columns, a spring group carried by said frame at the bottom of said bolster opening and supporting said portion, downwardly facing surfaces on said portion extending inwardly from the sides thereof, and means associated with said surfaces for additionally supporting said portion from said frame, said means comprising friction shoes frictionally engaged with friction faces on respective columns, each shoe and the related surface having a mutually engaged area respectively, one of which is curved and the other of which is substantially flat, as seen in longitudinal vertical section through said frame, all 25 of said areas being entirely disposed between spaced transverse vertical planes defining opposite longitudinal extremities of said group, wedge means housed in said portion and presenting surfaces on said areas being engaged with respective 30 columns, each shoe and the related surface having a mutually engaged area respectively, one of which is curved and the other of which is substantially flat, as seen in longitudinal vertical section through said frame, all of said areas being entirely disposed between spaced transverse vertical planes defining opposite longitudinal extremities of said group, wedge means housed in said portion and presenting 35 surfaces on said areas being engaged with respective columns, each shoe and the related surface having a mutually engaged area respectively, one of which is curved and the other of which is substantially flat, as seen in longitudinal vertical section through said frame, and spring means independent of said group compressed between said frame and said wedge means for urging the latter upwardly and thereby maintaining the shoes in simultaneous engagement with respective surfaces 40 and respective column faces, whereby part of the reaction of said spring means is transmitted by means of said areas from the wedge means to the shoes and thence to said surfaces.

WALTER L. SCHLEGEL, JR.
